(57) **CLAIM**

The ornamental design for an automotive transmission cooler as shown and described.

DESCRIPTION

FIG. 1 is a perspective view of the automotive transmission cooler according to the present application;

FIG. 2 is a rear view of FIG. 1;

FIG. 3 is a front view of FIG. 1;

FIG. 4 is a side view of FIG. 1;

FIG. 5 is a side view of FIG. 1;

FIG. 6 is a bottom view of FIG. 1; and,

FIG. 7 is a top view of FIG. 1.

The broken line showing is included for the purpose of illustrating unclaimed subject matter and forms no part of the claimed design.

The shade line showing is included for the purpose of illustrating contour and not surface ornamentation.
